CLAIM

The ornamental design for a combination cigar band and stand, as shown and described.

DESCRIPTION

FIG. 1 is a front perspective view of the combination cigar band and stand, showing the new design in an environment of use;

FIG. 2 is a bottom perspective view thereof;

FIG. 3 is another front perspective view thereof, shown with environment removed for clarity of disclosure;

FIG. 4 is another bottom perspective view thereof;

FIG. 5 is a left side view thereof;

FIG. 6 is a front view thereof;

FIG. 7 is top view thereof;

FIG. 8 is a front view of the combination cigar band and stand in a disassembled orientation;

FIG. 9 is a front perspective view of the combination cigar band and stand in a disassembled orientation;

FIG. 10 is a front perspective view of the combination cigar band and stand in an assembled orientation;

FIG. 11 is a bottom perspective view of the combination cigar band and stand in an assembled orientation; and,

FIG. 12 is a rear perspective view of the combination cigar band and stand in an assembled orientation.

The broken lines illustrate environmental subject matter only and form no part of the claimed design.

1 Claim, 5 Drawing Sheets
